U.S. Cl. D9—219

FIG. 1.

FIG. 2.

FIG. 3.

FIG. 4.

FIG. 5.

FIG. 6.

FIG. 1 is a bottom plan view of a molded packaging tray for meat or the like showing our new design;

FIG. 2 is an elevational view;

FIG. 3 is a top perspective view thereof;

FIG. 4 is a bottom plan view showing a modified form of our new design;

FIG. 5 is an elevational view; and

FIG. 6 is a top perspective view thereof.

The characteristic feature of the design resides in the inverted V-shaped ribs forming the open-window bottom which is like brick-work configuration, in combination with a peripheral rib surrounding the open-window bottom portion with a gutter or channel between such peripheral rib and the end and side walls with secondary ribs extending through such gutter or channel and merging into the end and side walls, as shown.

This application is a continuation-in-part of application Ser. No. D. 110,352 filed Jan. 27, 1971, now Pat. No. D. 225,213 issued Nov. 28, 1972.

We claim:

The ornamental design for a molded packaging tray for meat or the like, as shown and described.
